UNITED STATES PATENT OFFICE.

HENRY H. SESSIONS, OF CHICAGO, ILLINOIS, ASSIGNOR TO THE STANDARD COUPLER COMPANY, OF NEW JERSEY.

CENTER-BEARING FOR RAILWAY-CARS.

SPECIFICATION forming part of Letters Patent No. 605,522, dated June 14, 1898.

Application filed January 21, 1898. Serial No. 667,429. (No model.)

To all whom it may concern:

Be it known that I, HENRY H. SESSIONS, a citizen of the United States, residing at Chicago, in the county of Cook and State of Illinois, have invented certain new and useful Improvements in Center-Bearings for Railway-Cars; and I do hereby declare the following to be a full, clear, and exact description of the same, reference being had to the accompanying drawings, forming part of this specification, and to the letters of reference marked thereon.

This invention relates to improvements in railway-car construction, and particularly to means for uniting the car-body and trucks, the invention being more especially, though not exclusively, adapted for use in connection with passenger-cars and passenger-cars of the vestibule type, the objects of the invention being to secure a more flexible connection between the trucks and car-body, whereby in turning curves the axial lines of adjacent car-bodies will meet centrally instead of being shifted transversely with relation to each other, as in the prior constructions, and at the same time to insure the steady and practically firm connection between the parts at all times.

Referring to the accompanying drawings, Figure 1 is a diagrammatic illustration of the positions assumed by the abutting ends of two adjacent cars, as ordinarily constructed, in turning a curve. Fig. 2 is a similar view showing the correct position of such bodies with relation to each other and which it is the object of my invention to secure. Fig. 3 is a side elevation, partly in section, showing a center-bearing as applied to the truck-bolster, such parts being constructed in accordance with my present invention. Fig. 4 is a top plan view of the structure shown in Fig. 3 with parts shown in section. Fig. 5 is a cross-sectional view with parts shown in elevation, the structure depicted in the Figs. 3, 4, and 5 being specially adapted to four-wheel trucks. Figs. 6, 7, and 8 are views corresponding to Figs. 3, 4, and 5 and showing the construction adapted for six-wheel trucks. Figs. 9 and 10 are elevations, one-half in section, corresponding to Figs. 3 and 5 and showing

the complete truck with the swing-centers in place.

Like letters of reference in the several figures indicate the same parts.

Referring particularly to Figs. 3, 4, and 5, the letter A indicates a truck-bolster, which in this instance is preferably of compound construction and adapted to extend transversely across the trucks. It is composed, as shown, of two channel-irons $a-a$, arranged one on either side, with a filling a' of wood at each end, bolted between the two channel-irons, and an external plate or filling for the channel-irons on each side, (lettered a^2 .) This truck-bolster is adapted to be supported on springs S, Figs. 9 and 10, which springs are in turn mounted on a spring-plank T, carried by the usual swing-hangers U. Such arrangement being well known in the art, I have not deemed it necessary to illustrate the same herein, save in connection with the four-wheel-truck construction.

The filling a' is cut away centrally of the truck-bolster, and the space thus left is adapted for the reception of the center-bearing B, which center-bearing is suspended upon links C, pivotally mounted in bearings D on the upper surface of the truck-bolster. These links C are in practice in the form of yokes, having their center portions at c provided with a flat upper surface, which co-operates with a corresponding flat surface at the bottom of the center-bearing block, the object of this being to insure a quick return of the bearing-block to its central position after having been swung laterally in either direction, for in such swinging movement the links or yokes C will be thrown into an inclined position and the contact between the center-bearing and yokes will be at one edge or the other of each of the yokes. In other words, the center-bearing will be slightly raised with relation to the truck-bolster by such swinging movement, and the force of gravity or the weight of the car-body resting upon the center-bearing will tend to return the parts quickly to the position shown in Fig. 3.

In the preferred construction the center-bearing is provided with a bottom-plate E, upon which it is centrally maintained by a

downwardly-extending projection or hub *e*, and at each side of this bottom plate *E* inverted channel-irons *F* are secured to constitute the bearings within which the flat faces 5 of the bottom portions *c* of the links or yokes *C* are received. The center-bearing also has in its top surface the usual concave *G* for the reception of the bearing on the coöperating member carried by the body-bolster, and it 10 is vertically perforated for the passage of the usual king-bolt. In adapting this construction of center-bearing for six-wheel trucks, wherein a truss is formed by the center-bearing arch-bar and center-bearing inverted arch-bar extending longitudinally of the trucks, I 15 preferably adopt the construction shown in Figs. 6 to 8, inclusive, and by reference to these figures it will be seen that the longitudinal trusses formed by the center-bearing 20 arch-bars *H* are located one on each side of the center-bearing, and connecting these trusses are two relatively short channel-irons *I*, securely fastened in place between the arch-bars and trusses formed thereby by bolts *i*. 25 These transverse channel-irons *I* have formed upon them or support bearings *D*², corresponding to the bearings *D* and adapted to carry swing links or yokes *C*², corresponding to the yoke *C*. 30 The specific construction of the center-bearing itself is similar to that hereinbefore described and will not be again described, like letters being applied thereto, as in Figs. 3 to 5. The flat faces *K* of the channel-irons *a* and 35 I prevent any movement of the yokes or links *C* *C*² longitudinally of their axes, but permit them to swing freely in a transverse direction, and in order to give a greater element of safety and provide against possible accidents should one of these yokes become broken 40 the center-bearing itself is in each instance preferably provided with a transverse lug or projection *L*, which overhangs the channel-irons *a* and *I*, in position to catch and support the center-bearing should it drop but a 45 very short distance farther than would be permitted by the links or yokes *C* *C*² themselves if in proper working order. In a car or cars having the center-bearing supported 50 in this manner the tension of the draft-rigging will be sufficient to maintain the axial lines of the car-bodies in registry at their meeting points in turning on ordinary curves, as indicated in Fig. 2, where the axial lines 55 are lettered *M*, thereby overcoming the tendency of the buffing mechanism or vestibules to rub on each other or shear laterally, as would otherwise be the case. Strain upon the vestibules or platform is consequently to a 60 great measure overcome and the life and durability of these parts greatly prolonged.

It is obvious that while I have described the swing links or yokes as having flattened

bearing-surfaces each of them may be provided with two distinct bearing-surfaces somewhat widely separated, or, in other words, the central portion of the flattened surfaces may be cut away, as indicated, for instance, by the dotted lines *O* in Fig. 6, and the same results be secured. 65

Having thus described my invention, what I claim as new, and desire to secure by Letters Patent, is—

1. The combination with the truck-bolster mounted on swing-hangers whereby it may 70 move transversely, of swing links or yokes journaled on said bolster and the center-bearing mounted on said swing-links to move transversely; substantially as described.

2. The combination with the truck-bolster 80 or center-bearing support, the channel-irons incorporated therein with their flanges turned outwardly and the swing links or yokes suspended on and between said channel-irons to swing transversely of the car-body, of the 85 center-bearing mounted directly on the depending portions of said swing links or yokes and coöperating with the inner faces of the channel-irons to prevent movement longitudinally of the car; substantially as described. 90

3. The combination with the truck-bolster or center-bearing support, the swing links or yokes journaled therein and having at their lower portions flattened bearing-surfaces, of the center-bearing resting directly upon said 95 swing links or yokes and having flattened bearing-surfaces coöperating with the flattened bearing-surfaces of the swing links or yokes, whereby the center-bearing is caused to return to its central position; substantially 100 as described.

4. The combination with the truck-bolster or center-bearing support and the swing links or yokes journaled therein and having flat bearing-surfaces on their depending portions, 105 of the center-bearing, the supporting-plate underlying said center-bearing and the recessed bearings on said supporting-plate having flat bearing-surfaces on which the depending portions of the swing links or yokes 110 seat; substantially as described.

5. The combination with the truck-bolster or center-bearing support and the swing links or yokes journaled therein and having the flattened depending portions, of the center-bearing, the supporting-plate underlying the center-bearing and the inverted channel-irons on said supporting-plate, in which channel-irons the flattened portions of the swing 115 links or yokes seat; substantially as described. 120
